UNITED STATES PATENT OFFICE.

CHARLES R. MAGUIRE, OF BALTIMORE, MARYLAND.

ASH-SIFTER.

SPECIFICATION forming part of Letters Patent No. 366,492, dated July 12, 1887

Application filed December 2, 1886. Serial No. 220,463. (No model.)

To all whom it may concern:

Be it known that I, CHARLES R. MAGUIRE, a citizen of the United States, residing at Baltimore, in the State of Maryland, have invented certain new and useful Improvements in Ash-Sifters, of which the following is a specification.

My invention relates to certain improvements in ash-sifters of that class which have revolving drums, and is illustrated in the accompanying drawings, in which—

Figure 1 is an elevation giving a part side and part sectional view. Fig. 2 is an end elevation of part of the ash-sifter. Fig. 3 is an end view of the drum, showing its lid open. Fig. 4 is a perspective view of one of the boxes, showing the ash-funnel attached.

The ash-sifter comprises, besides the cylinder, three principal parts—the cylinder-supporting frame A, mounted on legs b, and the two boxes C C', one for the top and the other for the bottom. These three parts together form an enclosure for the cylinder.

The cylinder D may be made of woven wire 25 or perforated sheet metal. At each end it has a head, e, while a shaft, f, extends longitudinally through the cylinder and both heads. At one end this shaft has a crank, f'. The cylinder and shaft are supported in the frame A, and the shaft has bearings g in the ends of the frame, whereby the cylinder may be turned. The cylinder has a hinged lid, h, provided on its free meeting edge with a straight rod, i, whose ends project beyond the heads e. Each head has pivoted to it at k a hook, l, which projects in such position as to engage with the projecting end of the said rod i. A spring, m, has one end fixed to the head e, and the other end bears against the hook l 40 and keeps said hook pressed toward the rod i.

The effect of the spring, therefore, is to prevent the hook from accidentally disengaging from the rod, and thereby insures that the lid will not open while the cylinder is being turned. The legs b, on which the frame A is mounted, sustain the frame when it is not resting on the lower box, C', as shown in Fig.

2. These legs also serve to adjust the position of the lower box with respect to the frame A, 50 so that the edges of the two will coincide or fit

together. The upper ends, b', of the legs in like manner adjust or regulate the position of the upper box. The upper box, C, and lower box, C', have the same shape and dimensions, and are interchangeable—that is, the one shown as on top of the frame may be placed below it and the one shown below may be placed above.

The boxes have handles n, whereby they may be readily lifted. The combination of the frame A and legs with the cylinder and the interchangeable upper and lower boxes insures a tight inclosure when the sifting operation is going on, provides a receptacle for the ashes as they drop from the cylinder, and when the lower box, containing the ashes, is removed the upper box, which has served as a cover, may be placed below to receive the screened coals as they are dumped from the cylinder through its open lid.

The frame and the boxes may be square or 70 round, and may be made of wood or metal.

One of the boxes is provided at one side with a hinged door, O, the hinges being at p. The bottom q of the door is flush with the bottom q' of the box. A funnel-shaped chute, 75 R, has at its large end flanges s, and the large end fits snugly in the door-opening, while the said flanges take on or against the inner wall of the box, as shown in Fig. 4. Thus the funnel-shaped chute is closely connected with the box. 80 It will be understood that the chute may be readily detached from the box. One of the boxes is thus provided for the purpose of readily placing the mixed ashes and coal in the cylinder. This will be understood if we 85 suppose the upper box to be removed from the frame A and the lid h of the cylinder to be open. If now, the box has the funnel-shaped chute adjusted in position and contains the mixed ashes and coal which are to be sifted, 90 the latter may be readily placed in the cylinder through the lid-opening. When this has been done, the funnel-shaped chute R may be detached, the door O closed, and the box placed upside down as a cover on the frame A.

The door and funnel-shaped chute may be rigged at either side or end of the box.

One or both of the boxes may be provided with lids T, whereby when the box contains ashes the latter may be closely confined and 100

guarded from the effects of wind. To adapt the box so that its edges u will properly fit on the upper or lower edges v of the frame A, a special mode of hinging the lids is employed, 5 consisting of turning one edge of each lid into a tubular form, as at w . The lid thus takes position at one side of the box. A rod, x , passes through the tubular part, and at the ends of said tubular part both ends x' of the rod are 10 bent at a right angle and take position around the corner of the box, and said ends x' are secured by a pivot-pin, y , to the box ends, while the lid T has position at the box side. The two lids being hinged in this manner at opposite sides, both of them may be turned up 15 and over the box, where their meeting edges z will unite or come together to close the box; or each lid may be turned, as in Fig. 1, against the side of the box, whereat it is hinged. Thus 20 placed, the lids will not interfere with the function of the box when the latter is used in connection with the frame A.

Having described my invention, I claim and desire to secure by Letters Patent of the United 25 States—

1. In an ash-sifter, the combination of a frame, A, mounted on legs b , a revoluble cylin-

der, and two removable interchangeable boxes of the same shape and dimensions, one above and the other below the said frame, for the 30 purpose set forth.

2. In an ash-sifter, the combination of a frame, A, a revoluble cylinder in the said frame, two removable boxes, one above and the other below the said frame, one of said 35 boxes having at one side a door, and a removable funnel-shaped chute for connection in the door-opening, for the purpose set forth.

3. In an ash-sifter, the combination of a frame, A, a revoluble cylinder in the said 40 frame, two removable boxes, one above and the other below the said frame, one of said boxes having two lids, each hinged at an opposite side, substantially as set forth, whereby the lids may serve to close the box, or each lid 45 may be turned against the side of the box, whereat it is hinged.

In testimony whereof I affix my signature in the presence of two witnesses.

CHARLES R. MAGUIRE.
